UNITED STATES PATENT OFFICE.

OWEN B. PARKER, OF WOODVILLE, MASSACHUSETTS.

IMPROVED BOOK-HOLDER.

Specification forming part of Letters Patent No. **55,897**, dated June 26, 1866.

To all whom it may concern:

Be it known that I, OWEN B. PARKER, of Woodville, in the county of Middlesex and State of Massachusetts, have invented a new and useful Book Holder or Stand; and I do hereby declare the same to be fully described in the following specification and represented in the accompanying drawings, of which—

Figure 1 is a front view, and Fig. 2 a vertical section, of it.

In such drawings, A and B are two bars or yokes, each of which is provided with two projecting lips, *a a* or *b b*, arranged as represented. The two bars are connected by two elastic or extension bands, C C, which may be provided with buckles or metallic slides *c c*, by which they may be taken up or extended, as circumstances may require, in order to fit the holder to a book, whatever may be its length. Each of the elastic bands is attached to the upper bar, A, and goes through a slot made in the lower bar, and from thence is led to and connected to the slide *c*, made like the frame of a shoe-buckle, and applied to the band so as to slide on it, the band going down through it in manner as shown in Fig. 3, which is a lengthwise section of the band and slide.

There is also applied to the lower bar, and so as to be capable of freely revolving on it, two arms, D D. Each of these arms consists of two pieces of wood or metal, *d e*, hinged together at two of their ends and connected by a spring, *f*. The lower piece, *e*, projects from the bar B at right angles, and has a projection or finger, *g*, extending from it, as represented, such part *e* being so affixed to the bar B as to be capable of being revolved therein to enable the finger *g* to be raised from a horizontal up into a vertical position. Ordinarily the upper portion, *d*, of the arm D should stand at an acute angle with the part *e*.

A top view of the bar B with its appliances is shown in Fig. 4.

A hole, *h*, is bored or made through the middle part of the upper bar, A, and there is attached to the middle of the other bar, B, a piece of ribbon, *i*, provided with a loop or shoe, *s*, at its free end. This loop is designed to receive the lower end of a brace or prop, *k*, when the upper end of such prop or brace is inserted in the hole *h*.

The purpose of the apparatus is to hold a book open, in order that it may be read from to advantage. In using it the back of the book is to be placed on the middle of the lower bar, B, and with the covers inserted in the spaces between the bar and its two lips. Next the upper bar is to be extended, and the upper edges of the cover of the book are to be brought into the spaces between the bar and its lips. This having been done, the arms D may be turned so as to bring their upper parts, *d d*, upon the pages when the book may be open.

The finger *g* to each arm D serves as a lever or handle to enable a person to readily rotate the arm for the purpose of moving its part *d* either on or off the book. The fingers may also be employed to hold the leaves open, in which case the said fingers would have to be turned over or upon the leaves.

By means of the elastic or extension bands C C the apparatus may easily be adapted to a book of a duodecimo, octavo, or quarto size.

The prop, when inserted in the upper bar and the loop *s* of the ribbon, will serve to support the apparatus and a book on and at one inclination to a table. This prop may be hinged to the upper bar, or it may be constructed so as to admit of being extended in length to render it useful for books of different sizes.

What I claim as my invention is—

1. The combination as well as the arrangement of the two bars A B, their lips *a a b b*, and leaf-holders or arms D D with the elastic bands C C.
2. The combination and arrangement of the brace-hole and looped strap or ribbon with the two bars A B and their lips *a a b b*, the elastic connections C C, and arms D D.
3. The combination and arrangement of the brace or prop and the looped strap with the two bars A B, their lips *a a b b*, elastic connections C C, and arms D D.
4. The combination of the fingers *g g* with the arms D D, the bars A B, their lips *a a b b*, and elastic connections C C, the whole being as and for the purpose set forth.

OWEN B. PARKER.
